UNITED STATES PATENT OFFICE.

JAMES SWEENEY MAHER, OF KENNARD, OHIO.

WIRE FENCE.

SPECIFICATION forming part of Letters Patent No. 555,823, dated March 3, 1896.

Application filed June 13, 1894. Serial No. 514,480. (No model.)

To all whom it may concern:

Be it known that I, JAMES SWEENEY MAHER, a citizen of the United States, residing at Kennard, in the county of Champaign and State 5 of Ohio, have invented certain new and useful Improvements in Wire Fences; and I do hereby declare that the following is a full, clear, and exact description of the invention, which will enable others skilled in the 10 art to which it pertains to use the same.

This invention relates to certain new and useful improvements in wire fences.

The object of my invention is to provide for preventing the horizontal wires from being 15 spread apart at places between the posts and also to enable the posts to be placed farther apart, and this object I carry into practice by means of vertical wires placed across the line-wires and held thereto so that the line-wires 20 cannot move up and down on the vertical or cross wires and so that the vertical or cross wires cannot move laterally on the line-wires, the holding means consisting of perforated plates or disks through which the 25 line and vertical or cross wires are placed, and also additionally of wrapping or holding wires which are wrapped about the intersecting line and vertical wires and against the perforated plates to aid in preventing the latter 30 from loosing their grip upon the line and vertical or cross wires.

In the accompanying drawings, on which like reference-letters indicate corresponding parts, Figure 1 is a side elevation of a panel 35 of wire fence constructed according to my invention; and Fig. 2, a detail sectional view on the line *x* *x*, looking in the direction of the arrow.

Two posts are shown to which the line-wires 40 B are attached in any convenient or approved manner and are drawn taut by the usual means. At intervals between these posts I place across the line-wires vertical or cross wires A, the distance between them and the 45 number of them being governed by local conditions and the uses to which the fence is to be put varying with the character of stock to be fenced in.

The wires A and B are held together or interlocked by the gripping action of perforated

plates or disks C fashioned after the manner of washers. The perforations in these disks are of such size compared to the size of the wires A and B that when the latter are placed at right angles after being put through the 55 perforations the disks will assume an angular position and the wires will bind against the edges of the perforations and cause the disks to grip both sets of wires. This gripping is so severe and intense that the vertical or cross wires cannot be moved laterally by ordinary strains or blows which by chance they may be subjected to, and is so severe that the horizontal wires cannot be moved along the vertical or cross wires by the ordinary or casual strains or blows they are subjected to. But further to insure the rigidity 65 of the structure and to prevent slipping of the wires A and B on each other beyond all question, I provide what I term a "wrapping" 70 or "holding" wire D, which I wrap around the wires A and B at their intersection, placing it close against the plates or disks and then carrying it down over the lower edge of the disks or plates and along the vertical wire to 75 the next intersection, where I similarly wrap it, and so on to the last wire B, where its end is tightly wrapped around the wire B. The upper end of the holding-wire is similarly wrapped around the upper wire B and may 80 pass through the perforation of the disks or plates on the upper wire. This wrapping or holding wire so binds against the disks or plates and so additionally holds the horizontal and vertical wires that all movement of either 85 on the other is absolutely prevented.

The fence here described I have built in considerable quantities, and the same is in practical use.

Having thus fully described my invention, 90 what I claim as new, and desire to secure by Letters Patent, is—

1. In a wire fence, the combination with line-wires and vertical or cross wires intersecting the same, of perforated disks or plates 95 through which said wires are run, the plates or disks being at the intersection of said wires and standing at an angle thereto and gripping with the walls of the perforation against said wires.

2. In a wire fence, the combination with line-wires and vertical or cross wires intersecting the same, of perforated disks or plates through which said wires are passed at the points of 5 intersection, said disks or plates standing at an angle and gripping said wires, and a holding or wrapping wire engaging with the disks or plates and acting to additionally bind them against the other wires.

JAMES SWEENEY MAHER.
